UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING-MACHINE.

1,386,636.

Specification of Letters Patent.

Patented Aug. 9, 1921.

Application filed November 25, 1918. Serial No. 263,975.

To all whom it may concern:

Be it known that I, ALFRED G. F. KUROWSKI, a citizen of the United States, formerly a citizen of Germany, residing in Brooklyn 5 borough, in the county of Kings, city and State of New York, have invented certain new and useful Improvements in Typewriting-Machines, of which the following is a specification.

10 This invention relates to typewriting machines, and more particularly to tabulating mechanism.

The primary object of the invention is to provide an improved tabulating mechanism capable of use in a number of different forms of tabulation, and including means for setting the mechanism for different forms of tabulation, as well as improved means for performing certain kinds of tabulation.

20 In the embodiment of the invention herein disclosed, with the mechanism set for positioning the paper carriage by combined decimal-tabulation and column-selection, depression of a decimal key will move a secondary carriage or sub-carriage to a position corresponding to the order of the decimal key depressed, and will effect latching of said sub-carriage in such position as long 25 as the decimal key is held depressed.

Following the setting of the sub-carriage, depression of a selected column-key will lift one of a set of pawls, suitably supported on said sub-carriage, into position to be struck 30 by the corresponding column-stop, release of the paper carriage also being effected by depression of the column-key. Engagement 35 of a column-stop with the corresponding pawl will effect rocking of a frame on which the pawls are mounted, and by suitable connections raise a stop pivoted on the sub-carriage into position to engage the column-stop and thereby arrest the paper carriage. 40 It will be understood that the stress incident 45 to arresting the paper carriage will be transmitted to the latching means.

Another feature of the invention resides in the means for setting the mechanism for different kinds of tabulation. In this connection, it is pointed out that the machine 50 is also provided with means for decimal tabulation in successive columns. The setting means includes a lever mounted for

movement from front to rear, and for movement to either right or left from the 55 rear position. With the lever in front position, the machine is set for combined decimal tabulation and column-selection by a single movement of the paper carriage. With the lever in rear position, the mechanism is set either for decimal-tabulation in successive columns by means of the decimal 60 keys, or for a column-selection by means of the column or column-selecting keys.

A further feature of the invention resides 65 in the provision of locking means whereby movement of the setting lever from its rear position to the left will lock the column-selecting keys, whereas movement to the right will lock the decimal keys. 70

Other features and advantages will hereinafter appear.

In the accompanying drawings,

Figure 1 is a vertical section taken from front to rear, with parts omitted to simplify 75 the showing. In this view, the mechanism is set for combined decimal-tabulation and column-selection.

Fig. 2 is a plan view of the two sets of tabulating keys and the mechanism for determining the operative connection between 80 said keys and the tabulating mechanism proper.

Fig. 3 is a front view in vertical section, showing the tabulating mechanism at the 85 rear of the machine.

Fig. 4 is a front view in vertical section, showing the central set of plungers and the corresponding stop bar with stops mounted thereon. 90

Fig. 5 is a detail view partly in section, showing the position of the parts after depression of decimal key, but before depression of a column-selecting key, when the mechanism is set for combined action. 95

Fig. 6 is a view similar to Fig. 5, showing the parts in position at the end of a combined tabulating action.

Fig. 7 is a perspective view of the sub-carriage and enough of the associated parts 100 to make the operation clear.

Fig. 8 is a sectional view in side elevation of the parts shown in Fig. 2.

Fig. 9 is a sectional view taken along the line 9—9 of Fig. 8 looking in the direction 105 of the arrows.

Fig. 10 is a front elevation of the key-locking device with the handle in position to lock the column-selecting keys.

Fig. 11 is a view similar to Fig. 10, but 5 with the decimal keys locked.

Fig. 12 is a view showing the locking device ineffective and the controlling handle in position for combined decimal-tabulation and column-selection.

10 Fig. 13 is a perspective view partly in section, showing the connections of the operating handle with the rocking frame, the locking device, and the link through which the position of the interponents is determined.

Character keys 1 act through connections, not shown, to swing type-bars 2 against the platen 3 mounted on paper carriage 4. Said paper carriage 4 is mounted for sliding 20 movement on rods 5 and 6 and urged toward the left of the machine by the usual strap 7 and spring drum 8. Control of said carriage 4 is attained by the usual escapement mechanism, in which rack bar 9, pivotally supported on said carriage 4 by means of 25 arms 10, meshes with a pinion 11 having the usual one-way connection with the escapement wheel 12. Said escapement wheel is controlled by means of the usual 30 fast and loose dogs 13 and 14, respectively, and these dogs are, in turn, controlled by means of a frame 15 including a universal bar which is struck by the usual heel on a type-bar 2, at the end of a printing stroke.

35 At the rear of the machine, provision is made of a stop bar 16 carrying column-stops 17, having their lower portions of progressively increased length to correspond to the different columns. A locking shaft 18 serves 40 to hold said stops 17 in adjusted position.

Provision is made of another stop bar 19 carrying stops 20 normally raised to a position of non-use, but mounted so as to be capable of movement to depressed position.

45 Coöoperating with said stops 20 are plungers 21 having their upper ends spaced at letter-space distances apart, and guided for sliding movement in comb or plate 22. Said plungers 21 are guided at their lower ends 50 by means of a pin 23 engaging in slots 24, and are held in their lowest position by means of springs 25. Each of said plungers 21 is provided with a shoulder 26 engaging with a short universal bar 27 mounted on

55 arms 28 carried by a shaft 29. Rocking of said shaft 29 due to the lifting of any of said plungers 21 will act through an arm 29^a and link 30 to rock lever 31, pivoted at 32 on a fixed portion of the frame, and thereby 60 lift rack bar 9 from engagement with pinion 11. Upon reference to Fig. 1, it will be seen that lifting of rack bar 9 is effective through a wheel 33 engaging the under side thereof.

The mechanism thus far described is sub-

stantially the same as in my prior application, Serial No. 170,354, filed May 23, 1917. 65

At the front of the machine, provision is made of column-selecting keys 34 numbered from "1" to "10", inclusive, and of ten decimal tabulated keys 35 marked, respectively, 70

$\dots, 1, 10, 100, \frac{1}{T}, \frac{10}{T}, \frac{100}{T}, \frac{1}{M}, \frac{10}{M}, \frac{100}{M}.$

For convenience, keys 34 will be referred to as either column-selecting keys or column-keys, 75 and keys 35 as decimal keys, decimal tabulator keys, or denominational keys.

With the mechanism set for combined decimal-tabulation and column-selection, depression of any decimal key but the decimal point key will cause the corresponding lever 36 to engage a hook 37 on a frame 38 pivotally mounted on shaft 39, and act through arm 40 connected to said frame 38 to effect, through interponent 41, movement 85 of bell-crank 42 against the action of spring 43. Said bell-crank 42 is provided at its upper end with slot 44, into which projects a pin 45 mounted on a sub-carriage 46 supported at its rear on wheels 47 and 90 at its front by wheels 48, all of said wheels being mounted on fixed portions of the frame. Movement of sub-carriage 46 to the right is limited by an adjustable stop or screw 46^a positioned on said sub-carriage in 95 position to engage a fixed part of the frame and movement to the left is limited by engagement of bell-crank 42 with a portion of a fixed guiding bracket 42^a. As shown in Fig. 9, hooks 37 gradually decrease in 100 length from left to right, and are so proportioned that the movement of said frame 38 by depression of said decimal keys will be proportional to the denomination of the key depressed, and consequently movement 105 of said carriage 46 will correspond to the denomination of the decimal key depressed.

Mounted on pivot 49 on said carriage 46 is an arm 50 provided with a tooth 51 for engagement with a column-stop 17 in order 110 to arrest the paper carriage. Downward movement of said arm 50 is limited by a pin 52, and said arm is normally held in such downward position by means of a spring 53. The means for operatively positioning said tooth 51 will be described hereinafter.

Whenever one of the decimal key levers is operated to set the sub-carriage, it also acts through one of the set of interponents 115 54 to raise one of the set of plungers 55. These plungers 55 are spaced at letter-space distances apart at their upper ends, and are there guided in fixed parts of the frame. At their lower ends, said plungers 55 are 120 provided with slots 56 through which passes a pin 57. A spring 58 tends to hold each plunger 55 in its downward position, and

the downward movement of each of said plungers is limited by said pin 57. The plunger 55, which has been lifted by the corresponding key lever, is engaged by a latch 59 supported by a pivot 60 on the sub-carriage 46. Upon reference to Figs. 5 and 6, it will be seen that sub-carriage 46 and consequently latch 59 are carried slightly to the right of their stopping position, and that 5 later the carriage will be given a slight return movement to bring latch 59 into contact with the operatively-positioned plunger 55. Said latch is limited as to downward movement by a curved lug 61 and is held in 10 downward position by spring 62. Depression of a column-selecting key 34 acts through a corresponding key lever 63 pivoted on shaft 39 to project upwardly the corresponding plunger 64, the set of plungers 15 64 being mounted for a sliding movement at the rear of the machine. At their upper ends, plungers 64 are bent so as to present portions 65 extending transversely of the machine and arranged at regular intervals 20 from front to rear. Provision is made in each of said portions 65 of a slot 66 substantially equal in length to the path of movement of said sub-carriage 46. Extending into each of said slots 66 is a pin 67 carried by a pawl or thrust link 68. Said pawls 68 are supported on pivots 69 carried by frame 70 pivoted low down at 71 on said sub-carriage 46. Integral with said frame 25 70 is an arm 72 provided with a slot 73 into which projects a pin 74 carried on arm 50, carrying said stop tooth 51. It will be seen that actuation of any of said decimal keys will position said sub-carriage 46 in accordance with the order of said decimal key, and 30 subsequent depression of any column-key 34 will effect lifting from its normally ineffective position into operative position of its one of said pawls 68, and, at the same time, by means of shoulder 64^a formed on the corresponding plunger 64, effect release of the 35 paper carriage. Movement of the traveling carriage to the left will bring the column-stop corresponding to the column-selecting key depressed into engagement with the operatively-positioned pawl 68, which thus becomes an interponent, and, by rocking the 40 frame 70, operatively raises the tooth or counter-stop 51 into position to engage the selected column-stop and arrest the paper-carriage. It will be evident that the shock 45 due to the impact of the column-stop against the operatively-positioned pawl will be transmitted to the raised latching plunger 55 by the latch or bolt 59. 50 The means for setting the mechanism for different kinds of tabulation will now be described. At the front of the machine, provision is made of a controlling handle or lever 75 pivoted at 76, for movement from 55 front to rear, upon the member 77 supported 60 for turning movement in a slotted plate 78, which serves as a guiding device for the tabulating levers. Near its upper end, lever 75 is provided with slot 79, through which extends a pin 80 supported at its ends on 70 frame 81. Said frame 81 is rigidly connected to a link 82, and serves to transmit the movement of lever 75 to the other parts of the setting mechanism. Said link 82 is provided with a slot 83 through which shaft 75 39 passes, said slot being of sufficient size to permit free movement of said link 82. At its rear end, link 82 is connected to a shaft 84 supported on a frame 85, which is pivoted for rocking movement on pivots 86. Shaft 80 84 also serves to connect interponents 41 and 54 with the setting handle 75. 85 As shown in Fig. 1, with the handle 75 in forward position, interponent 41 furnishes an operative connection between arm 40 and bell-crank lever 42, and interponents 54 give operative connection between decimal-key levers 36 and plungers 55. When, however, handle 75 is moved to the rear (see Fig. 8), interponent 41 will be moved to the rear and 90 will no longer afford operative connection between arm 40 and bell-crank 42, and interponents 54 will serve to give operative connection between key levers 36 and plungers 21. With the setting handle in this 95 position, column-selection can be obtained by use of column-keys 34, and decimal-tabulation can be obtained by use of decimal keys 35. 100 Further provision is made of a T-slotted guide plate 87 for said lever 75. In its movement from front to back, lever 75 moves in the upright slot 88 of the T, and the transverse slot 89 at the upper end of said slot 88 permits movement of the setting handle to either right or left. Extending rearwardly from said lever 75 is a lug 90, which engages with a notch 91 in a bar 92 slidingly mounted by means of slots 93 therein engaging headed pins 94 supported 105 in guide-plate 78. Member 77 projects through a slot 92^a in said bar 92, said slot being of sufficient size so as not to interfere with the movement of bar 92 on said pins 94. The bar 92 is provided with projections 95 spaced at suitable distances apart, so that when the lever 75 is in central position, there will be no interference with depression of either decimal-key levers or 110 column-key levers, but upon movement of said handle 75 to the left from its rearward position, locking of the column-keys will be effected, and upon movement of said handle to the right, locking of said decimal keys will be effected. For the convenience 115 of the operator, the forward end of the upright portion of the T-shaped slot is designated by COMB., and the left and right 120 125

ends of the transverse slot by DEC. and COL., respectively, to indicate the selective actions of the handle.

With interponents 54 positioned to afford operative connection between key levers 36 and plungers 21, stops 20 must be set in position to coöperate with plungers 21. For this purpose, a stop-setting key 96 is provided. Depression of said stop-setting key 96 acting through lever 97, link 98 and arm 99 serves to rock shaft 100, and thereby, through arm 101 and link 102, rock lever 103 about its pivot 104. At its rear end, lever 103 is provided with a head 105 which serves to set the properly positioned stop 20 upon depression of key 96. Upon reference to Fig. 3, it will be seen that a stop 20 is provided for each letter-space position of the paper carriage. The stop-setting device, here described, is substantially the same as that shown in said prior application, No. 170,354, filed May 23, 1917, the only differences being those necessary to adapt said stop-setting device for use with the tabulating mechanism here shown.

Variations may be resorted to within the scope of the invention, and portions of the improvements may be used without others.

Having thus described my invention, I claim:

1. In a typewriting machine, the combination with a paper-carriage and feeding mechanism therefor, of a rack on said paper-carriage having means whereby column-stops may be adjustably positioned thereon, column-stops of different conformation corresponding to different columns mounted on said rack, a secondary carriage movable transversely of the machine, a rocking frame having pivotally mounted thereon a series of pawls arranged to coöperate with column-stops of suitable conformation, a movable stop member mounted upon said secondary carriage and connected with said rocking frame, so that, upon engagement of one of said pawls by a column-stop and consequent movement of said rocking frame, said movable stop will be moved into position to engage a column-stop on said rack and arrest the paper carriage, means to position the secondary carriage to correspond to the denomination selected, and means to selectively position said pawls.

2. In a tabulating mechanism, the combination with a traveling carriage, of a series of column-stops thereon having conformations corresponding to the different columns, a secondary carriage mounted on the frame for transverse movement thereon, a movable stop on said secondary carriage, a series of pawls mounted on said secondary carriage for coöperation, when in operative position, with the respective column-stops, mechanism whereby engagement of any of said pawls

by a column-stop will position said movable stop in the path of said column-stop, means for positioning the secondary carriage in accordance with the denomination selected, and means for operatively positioning the pawl corresponding to the column selected.

3. In a typewriting machine, the combination with a traveling carriage urged in one direction, of a set of column-selecting keys, a set of denomination-selecting keys, and means rendered effective by successive actuation of a denomination-selecting key and a column-selecting key for bringing the carriage to the selected position by a single movement, said means including a denomination-selecting carriage movable transversely of the machine, and denominational-selecting key-actuated means for operatively positioning said denomination-selecting carriage.

4. In a typewriting machine, the combination with a traveling carriage, of means for effecting movement of said carriage to any desired position by a single movement, said means including denominational keys, a denomination-selecting carriage movable transversely of the machine, denominational-key-actuated means for positioning the denomination-selecting carriage in accordance with the denominational key depressed, and latching means for said carriage effective while a denominational key is held in depressed position.

5. In a typewriting machine, the combination with a traveling carriage urged in one direction, of combined column-selecting and denomination-selecting means comprising a set of column-stops of progressively varied conformation mounted on said traveling carriage in predetermined positions, a secondary carriage movable transversely of the machine, a series of column-selecting pawls on said secondary carriage, a member on said secondary carriage for engaging a column-stop and thereby arresting the traveling carriage, a device universal to said pawls for moving said arresting member to operative position, means for selectively positioning said secondary carriage, and means for selectively moving said pawls into position to engage the corresponding column-stops.

6. In a tabulating mechanism, the combination with a traveling carriage urged in one direction, of controlling means therefor comprising denomination-selecting means including denominational keys, levers on which said denominational keys are mounted, a secondary carriage movable transversely of the machine, a secondary carriage-controlling bell-crank, a swinging frame having an arm for actuating said bell-crank but normally having no operative connection therewith, denominational-key-actu-

- ated means for giving said frame a movement in accordance with the denominational key depressed, a latch member on said carriage, latch plungers corresponding to the 5 denominational keys and normally in inoperative position, a rocking frame, an interponent pivotally connected to said rocking frame and affording operative connection between said bell-crank and said actuating 10 arm, and a series of interponents pivotally connected to said rocking frame and affording operative connections between the denominational key levers and said latch plungers.
- 15 7. In a tabulating mechanism, the combination with a traveling carriage, of controlling means therefor comprising a combined denomination-selecting and column-selecting means, denomination-selecting keys, column-selecting keys, denomination-selecting-key-actuated mechanism for setting up a preliminary condition in said combined means, column-selecting-key-actuated devices for completing the setting-up of said 20 combined means to effect the combined functions, means for effecting denominational tabulation in successive zones, a controlling member mounted for movement to three different positions, and controlling-member-actuated means effective in one position of said controlling member for rendering said combined means effective to produce the combined result, effective in the second position for locking said denomination-selecting keys and rendering said combined means effective for column-selecting only, and effective in the third position for locking said column-selecting keys and rendering effective said means for effecting denominational tabulation in successive zones.
- 25 8. In a typewriting machine, the combination with a traveling carriage, decimal keys, decimal-key levers, and column keys, of means for effecting different kinds of tabulation comprising a bell-crank, forward decimal-stops, rearward decimal stops, decimal-key-actuated means, including an arm underlying an arm of said bell-crank, for moving said bell-crank proportionally to the order of the decimal key depressed, an interponent affording operative connection 30 between said bell-crank and the actuating arm therefor, a set of interponents mounted for movement to positions between the decimal-key levers and the forward decimal stops, or to positions between the decimal-key levers and said rearward decimal stops, and a controlling device holding the set of interponents in forward decimal-stop-actuating positions when the bell-crank interponent is in effective position, and for holding the set of interponents in rearward decimal-stop-actuating positions when the bell-crank interponent is in ineffective position.
- 35 9. In a typewriting machine, the combination with a traveling carriage, of tabulating mechanism, including decimal keys and column keys, capable of use for different kinds of tabulation, tabulating-mechanism-setting means, a movable member for controlling said setting means, the tabulating mechanism being set for combined decimal-tabulation and column-selection by a single carriage movement with said movable member in one position, and set for either column-selection or decimal-tabulation for the second position of said movable member, and means effective with the movable member in the second position for locking either the decimal keys or the column keys.
- 40 10. In a typewriting machine having a carriage, the combination with a sub-carriage urged in one direction and a set of keys, of key-controlled means for moving said sub-carriage, in a direction opposite to that in which it is urged, to positions corresponding to the keys depressed.
- 45 11. In a typewriting machine having a carriage, the combination with a sub-carriage and means for urging said sub-carriage in one direction, of a set of keys, key-actuated means for moving said sub-carriage against the action of said urging means, to positions dependent upon the keys depressed, and latching means for retaining the sub-carriage in such positions.
- 50 12. In a typewriting machine having a carriage, the combination with a sub-carriage and means tending to hold the same in its normal position, of selective means for moving said sub-carriage to other positions, and latching means for retaining said sub-carriage in positions to which it has been moved by said selective means.
- 55 13. In a typewriting machine having a carriage, the combination with a sub-carriage urged in one direction and a set of keys, of key-actuated means for moving said sub-carriage to positions corresponding to the keys depressed, and sub-carriage-latching means, comprising a latch member on said sub-carriage and plungers for co-operating with said latch member, each of said plungers being moved to operative position by one of the sub-carriage-moving keys.
- 60 14. In a typewriting machine having a carriage, the combination with a sub-carriage and yielding means for holding the same in its normal position, of sub-carriage-positioning means including key-levers, and sub-carriage-latching means including a series of plungers and means for selectively moving said plungers to operative positions in accordance with the key-lever depressed.
- 65 15. In a typewriting machine having a carriage, the combination with a sub-carriage yieldably held in normal position and

6
a latching member on said sub-carriage, of a key-lever, a key-lever-actuated device to move said sub-carriage to a predetermined position, and a key-lever-actuated device to coöperate with said latching member to hold said sub-carriage in such predetermined position.

16. In a typewriting machine, the combination with a traveling carriage, of tabulating means therefor, comprising a series of column-stops mounted on said carriage, a sub-carriage yieldingly held in normal position, a stop-member mounted on said sub-carriage for movement to a position to engage said column-stops, column-selecting means for operatively positioning said stop-member upon the approach of the selected column-stop, means, including decimal keys, for selectively positioning said sub-carriage, 20 and latching means for holding said sub-carriage in selected position.

17. In a typewriting machine, the combination with a traveling carriage, of tabulating mechanism therefor comprising a set of differential column-stops on said carriage, a secondary carriage, means for moving said secondary carriage to selected position, a stop member mounted on said secondary carriage for movement into operative position 30 to engage said column-stops, column-selecting keys, and means actuated by said column-selecting keys and the column-stops to move said stop member into operative position.

35 18. In a typewriting machine, the combination with a traveling carriage, of tabulating means including a series of column-stops on said carriage, a sub-carriage, means for selectively positioning said sub-carriage, a stop member mounted on said sub-carriage, and means to position said stop member for engagement by said column-stops.

19. In a typewriting machine having a carriage, the combination with a movable 45 sub-carriage, of decimal keys, and decimal-key-actuated means for positively moving said sub-carriage to positions corresponding to the decimal keys depressed.

20. In a typewriting machine, the combination with a traveling carriage, of column-selecting means, means for coöoperating with said column-selecting means to obtain combined decimal-tabulation and column-selection by a single movement of the traveling 55 carriage, a decimal tabulating device, controlling means to render said coöoperative means ineffective and said decimal tabulating device effective, and means effective when said coöoperative means is ineffective 60 for locking either said column-selecting means or said decimal tabulating device out of action.

21. In a typewriting machine, the combination with a traveling carriage, of tabulating mechanism comprising column-selecting

plungers, column-selecting key levers for actuating said column-selecting plungers, a sub-carriage, a bell-crank connected to said sub-carriage for actuating the same, bell-crank-actuating means including an interponent, latching plungers for said sub-carriage, latching-plunger-actuating means including a set of interponents, and means for moving said bell-crank interponent to render said bell-crank-actuating means ineffective, and for moving the latching-plunger-actuating interponents to render said latching-plunger-actuating means ineffective. 75

22. In a tabulating mechanism, the combination with a traveling carriage, a series of 80 decimal keys, a series of column-selecting keys, a series of column-stops on said carriage, a series of decimal-key-actuated plungers, an intermediate device to afford stopping connections between said plungers and 85 said column-stops, decimal-key-controlled means for moving said intermediate device to positions in accordance with the plungers operatively positioned, a latching device to hold said intermediate device in position 90 with respect to operably positioned plungers, and means to establish a stopping connection between said intermediate device and selected column-stops.

23. In a tabulating mechanism, the combination with a traveling carriage, of a series 95 of decimal keys, a series of column-selecting keys, a series of column-stops on said carriage, a movable counter-stop, decimal-key-actuated means for positioning said counter- 100 stop transversely of the machine, and means operated by the column-selecting keys and the traveling carriage for positioning said counter-stop for engagement with the column-stop corresponding to the selected column. 105

24. In a tabulating mechanism, the combination with a traveling carriage, of a series 110 of decimal keys, a series of column-selecting keys, a series of column-stops on said carriage, a movable counter-stop, decimal-key-actuated means for positioning said counter-stop transversely of the machine, carriage-actuated means for moving said counter-stop into operative position for engagement 115 by a column-stop, and column-selecting-key-actuated means for determining the column-stop to be engaged by said counter-stop.

25. In a typewriting machine, the combination with a traveling carriage, decimal 120 keys and column-selecting keys, of tabulating mechanism for different kinds of tabulation, setting means therefor including a reciprocating bar through which the same is actuated, a device normally ineffective but capable of locking either the decimal keys or the column-selecting keys, a manually-operable member, and connections between said manually-operable member and both said reciprocating bar and said locking 125 130

device, whereby independent actuation of either said reciprocating bar or said locking device can be effected by said manually-operable member.

- 5 26. In a typewriting machine, the combination with tabulating mechanism settable for different forms of tabulation, a set of decimal keys and a set of column-selecting keys, of setting means for said tabulating mechanism including a reciprocable bar for actuating the same, means effective to hold said reciprocable bar in either front or rear position, means including a reciprocable member for locking the decimal keys by movement in one direction and for locking the column-selecting keys by movement in the opposite direction, a manually-operable controlling member, and connections between said manually-operable member and both said reciprocable bar and said reciprocable member, whereby movement of said manually-operable member to move said reciprocable bar will be idle with reference to said reciprocable member and vice versa.
- 25 27. In a tabulating mechanism, the combination with decimal keys, column-selecting keys and settable means for determining the form of tabulation, of a reciprocable bar for controlling said settable means, a transversely movable locking member ineffective in central position but effective upon movement in one direction to lock said decimal keys, and upon movement in the other to lock said column-selecting keys, controlling means for said reciprocable bar and said locking member including a manually-operable member, connections whereby forward or rearward movement of said manually-operable member will be active with respect to said reciprocable bar and idle with respect to said locking member, and transverse movement thereof will be active with respect to said locking member and idle with respect to said reciprocable bar, and guiding means for limiting said manually-operable member to movement in a path from front to rear and to transverse movement at a certain point of said path.
28. In a typewriting machine, the combination with a traveling carriage, of tabulating mechanism including decimal keys and column-selecting keys, means for setting said tabulating mechanism for different forms of tabulation, including a transmitting member through which said setting means is actuated, means, normally ineffective, for locking either said decimal keys or said column-selecting keys, a manually-operable member mounted for universal movement, connections between said manually-operable member and both said transmitting member and said locking means, whereby movement of said manually-operable member in a path to and from the front of the machine will be active with respect to said

transmitting member and idle with respect to said locking means, and transverse movement will be active with respect to said locking means and idle with respect to said transmitting member, and a guiding member for limiting said manually-operable member to movement in a path from front to rear, and a second path transverse to the first at a certain point therein.

29. In a typewriting machine, the combination with a traveling carriage, decimal keys and column keys, of a secondary carriage, decimal-key-actuated means for positioning said secondary carriage, including a member differentially moved in accordance with the decimal keys depressed, and an interponent through which said differentially moved member acts, latching means for said secondary carriage including a series of latching plungers individual to said decimal keys, operative connections between each of said decimal keys and the corresponding latching plunger, a series of interponents, each of which forms part of the operative connection between a decimal key and the corresponding latching plunger, column-selecting means for establishing a stopping connection between said secondary carriage and said traveling carriage, a decimal tabulating device including stop plungers, and a controlling member connected to all of said interponents to move the same in both directions, whereby, upon movement from one position to a second, the secondary-carriage-positioning-interponent will be moved to inoperative position and said series of interponents will be moved from operative position with respect to said latching plungers to operative position with respect to said stop plungers.

30. In a tabulating mechanism, the combination with a traveling carriage and decimal keys, of a secondary carriage yieldingly held in home position, decimal-key-actuated means for positioning said secondary carriage in accordance with the decimal keys depressed, means for establishing a stopping connection between said secondary carriage and said traveling carriage, and means for relieving the decimal keys from shock incident to stopping the traveling carriage.

31. In a typewriting machine, the combination with a carriage, of column-stops of progressively varied conformation adjustably positioned on said traveling carriage, a secondary carriage movable transversely of the machine, a series of movable members mounted on said secondary carriage for movement to operative positions to engage the corresponding column-stops but to permit passage of column-stops preceding said corresponding column-stops, decimal-tabulating means to position said secondary carriage, column-selecting means for operatively positioning said movable members,

and means operated by engagement of an operatively-positioned movable member by the corresponding column-stop for establishing a stopping connection between said 5 traveling carriage and said secondary carriage.

32. In a tabulating mechanism, the combination with a traveling carriage, of a series of column-stops on said carriage, a series of 10 plungers, denomination-selecting means for selectively moving said plungers to operative positions, an intermediate device to afford stopping connection between said plungers and said column-stops, means actuated by said denomination-selecting means 15 for moving said intermediate device to positions in accordance with the plungers operatively positioned, a latching device to hold said intermediate device in position 20 with respect to the operatively-positioned plungers, and means to establish a stopping connection between said intermediate device and selected column-stops.

33. In a tabulating mechanism, the combination with two elements having relative 25 traveling movement, of a series of column-stops on the first of said elements, a movable counter-stop on the second of said elements, decimal-tabulating means for positioning said movable counter-stop at a plurality of decimal places, column-selecting means, and means, controlled by said column-selecting means, for effecting engagement between said counter-stop and the 30 column-stop corresponding to the selected column.

34. In a typewriting machine, the combination with a traveling carriage and column-selecting keys, of a sub-carriage 40 adapted to be set for decimal tabulating, and interponents adapted to be set by said keys on said sub-carriage to arrest the traveling carriage.

35. In a typewriting machine, the combination with a traveling carriage, of tabulating mechanism including a sub-carriage 45 for determining the denomination, and means for selectively determining the column in which the carriage will be stopped, 50 including movable devices in said sub-carriage.

36. In a typewriting machine, the combination with a traveling carriage, of decimal-tabulating stops, and a column-selecting sub-carriage adapted to be interposed between the traveling carriage and the stops.

37. In a typewriting machine, the combination with a traveling carriage, of a sub-carriage adapted to be picked up, decimal 60 keys for determining where the sub-carriage shall be arrested, and column-selecting keys for determining at what column the traveling carriage shall pick it up.

38. In a typewriting machine, the combination with a traveling carriage, of a sub-

carriage, decimal keys for determining where the sub-carriage shall be arrested, interponents selectively settable on the sub-carriage to enable the traveling carriage to selectively pick it up, and keys controlling 70 the interponents.

39. In a typewriting machine, the combination with a traveling carriage, of column-stops on it, a decimal-positioned sub-carriage, and devices on the sub-carriage for 75 selectively arresting the traveling carriage by the column-stops at any decimal position of the sub-carriage.

40. In a typewriting machine, the combination with a traveling carriage, of column-selecting keys, decimal keys, interponents to enable the keys to be used separately or together, and a locking device for selectively locking the keys against operation.

41. In a typewriting machine, the combination with a traveling carriage, of column-stops, column-selecting keys, devices operated by said keys for selectively arresting the carriage by said stops, other column-stops, decimal counter-stops for said other column-stops, keys for said counter-stops, a universal bar operated at the actuation of any of said keys, interponents through which certain of said keys are effective, and means 90 for selectively locking said keys.

42. In a typewriting machine, the combination with a traveling carriage, of column-stops settable on it, decimal-tabulating keys, a sub-carriage for selectively arresting 100 the carriage in various columns, connections whereby the decimal keys make the sub-carriage effective at any desired decimal position, a second set of column-stops, and connections whereby said second set may arrest 105 the traveling carriage at the operation of a decimal-tabulating key.

43. In a typewriting machine, the combination with a traveling carriage, of decimal-tabulating keys, column-tabulating keys, 110 stops on said carriage, three sets of key-operated connections to arrest the carriage by the stops according to the kind of tabulating desired, and interponents between said keys and connections to determine what 115 connections may be effective.

44. In a typewriting machine, the combination with a traveling carriage, of decimal-tabulating keys, column-tabulating keys, stops on said carriage, three sets of 120 key-operated connections to arrest the carriage by the stops according to the kind of tabulating desired, interponents between said keys and connections to determine what connections may be effective, and a finger-piece shiftable to set said interponents and selectively lock said keys.

45. In a typewriting machine, in combination, a traveling carriage, a device mounted for movement along the path of 130

said carriage, a set of keys corresponding to different numbers, means driven by said keys for moving said device in a direction opposite to the letter-feeding direction, to 5 position said device a number of letter-spaces from its normal position corresponding to the value of the key depressed, and

means whereby said device may be connected with said carriage.
